UNITED STATES PATENT OFFICE.

CHARLES D. YOUNG, OF ALTOONA, PENNSYLVANIA.

TIE-PLATE FOR RAILWAYS.

1,242,300.

Specification of Letters Patent.

Patented Oct. 9, 1917.

Application filed July 6, 1915. Serial No. 38,274.

To all whom it may concern:

Be it known that I, CHARLES D. YOUNG, a citizen of the United States, residing at Altoona, in the county of Blair and State 5 of Pennsylvania, have invented certain new and useful Improvements in Tie-Plates for Railways, of which the following is a specification.

This invention relates to tie plates and particularly to that class of tie plates used for supporting railway rails upon wooden ties and has for its principal objects, the provision of a tie plate or rail support whereby the load upon the tie plate is 10 evenly distributed upon the surface of the tie beneath the plate; the provision of a tie plate whereby rocking of the tie or tie plate as the rail is deflected by the load, is minimized or entirely prevented; the provision of a tie plate that may be readily applied to the tie and rail and secured in place without the use of driven spikes; the provision of a tie plate that may be cheaply 15 formed from a rolled metal plate and which is durable and efficient; the provision of a tie plate that does not chafe the tie due to 20 improper distribution of the load; and such other objects as may hereinafter appear.

One embodiment of the invention and 25 modifications thereof are shown in the accompanying drawings wherein—

Figure 1 is a plan view of a tie plate; Fig. 2 is a side elevation of the tie plate; Fig. 3 is an end view of a tie showing the 30 tie plate assembled thereon with certain portions in section; Fig. 4 is a plan view of a railway construction showing the ties and tie plates in operative position; Fig. 5 is an end view of a tie showing a modified 35 form of tie plate mounted thereon; Fig. 6 is a sectional view showing a modified form of bolt insulating or protecting means and Fig. 7 is a side elevation of the tie shown in Fig. 6, showing the elements shown in 40 Fig. 6.

Referring to Figs. 1, 2, and 3, the device 45 consists of a metal plate 1 provided with a pair of struck-up lugs 2 and 3 for engaging the base flange of the rail 4. These lugs are for the purpose of securely holding 50 the rail in position and are diagonally

disposed with respect to the center line of the rail when in operative position. The inner edges 4 of the lugs 2 and 3 are inclined and because they are diagonally positioned permit the plate to be assembled with the rail when the plate is turned so that the center line A—A Fig. 1 is parallel with the rail as shown in dotted lines Fig. 4. In such position the lugs will clear the rail 60 flange, and when the plate is moved into operative position as shown in full lines in Fig. 4, the lugs will securely engage the rail flange and hold the rail in position.

Referring to Fig. 2, the lugs consist of 65 pieces of struck-up metal provided with clamping ends bent to conform to the contour of the rail web at the point of engagement and serve to hold the rail against both lateral and vertical displacement. While 70 the lugs shown are struck-up from the plate by a punching operation, such lugs may be cast on the plate, welded or otherwise secured for the purpose.

It has been found that where a tie plate 75 is used having a flat upper surface, the deflection of the rail between the ties caused by the moving wheels of the rolling stock, causes the load to be placed first on one edge of the plate, depressing the tie and plate 80 on that side, then on the center, straightening the tie again, and finally on the other edge of the plate causing the depression of the tie and plate on such side. The rolling 85 of a train over such a track causes a rocking motion of the tie which works the tie loose in the road bed and works the spikes loose from the ties and the plates loose from their seat. The rocking of the tie plate wears and chafes the tie at the point of contact and when lost motion has been started 90 the wear increases at an increasing ratio.

To prevent such wear and thereby increase the life of the rail, plate, and tie, the tie plate 1 is provided with a flat under 95 surface 6 adapted to fit solidly upon the upper face 7 of the tie 8 (see Fig. 3). The top surface of the plate is substantially flat at 9 between the points B—B, Figs. 1 and 3, and curves downward toward the edges 10 100 and 11. Normally the rail 4 rests upon the flat portion, the edges 10 and 11 at such

times being spaced from the rail. Preferably, the top surface of the tie plate is curved so that the edges of the plate are spaced about one sixteenth of an inch from 5 the bottom of the rail.

It will be seen that when the rail is normally supported adjacent the center of the plate, the pressure will be evenly distributed throughout the entire bearing surface there- 10 of and even through the rail is deflected to an extent that it bears upon a point between the center of the plate and the edge, the point of contact will be more or less general and therefore the load will be considerably 15 more distributed over the bearing surface than where the whole load rests upon the edge of the plate. The top surface of the plate may be curved from one edge to the other without the provision of a flat central 20 seat, the essential feature however being a plate having a firm or stable bearing upon the tie and a central bearing area for the rail of greater elevation than the edges of the plate so that normally the edges of the 25 plate are spaced from the bottom of the rail.

It has been found that where spikes are driven into wooden ties, the displacement of the fiber caused by the wedged spikes, disrupts the fiber adjacent the spike so that 30 such fiber is subject to deteriorating atmospheric action resulting in the loosening of the spike and eventual rotting of the wood surrounding the spike. Continual vibration of the loosened spike breaks the rotting fiber 35 and the spike soon becomes dangerously loose. In such cases it is often necessary to replace the ties before the balance of the tie, where the fiber has not been disturbed, has become affected by atmospheric condi- 40 tions.

To avoid such means of securing the rails to the tie as have proven injurious, the tie plate 1 is provided with a depending flange 12 adapted to engage the side 13 of the tie. 45 The flange is preferably reduced in thickness and provided with holes 14 through which bolts 15 project. The bolts pass through holes drilled in the tie, from one side thereof to the other, the head of the 50 bolts bearing against a washer plate 16, Figs. 3 and 4, while the other end is provided with the usual lock washer 17 and nut 18. The bolts 15 securely hold the tie plate 1 against vertical or lateral motion, and as 55 the bolts are inserted through drilled holes, the fiber is not disturbed, and as the holes are horizontally disposed, water cannot enter the hole. This construction results in longer life to the tie and a more secure rail 60 fastening.

To further protect the exposed parts of the securing means from climatic conditions, blocks 19 and 20, made of wood or other electrically insulating material are

nailed to the side of the tie and inclose the 65 ends of the bolts and all exposed metal parts below the top surface of the tie. These insulating covers also serve to prevent the grounding of the rail where the rail is used as an electrical conductor in conjunction 70 with signaling apparatus and the like.

Referring to Fig. 5, a modified form of the tie plate 1' is there shown having two depending flanges 12'-12' which securely clamp the tie plate to the tie. This construction, while less easily assembled under some circumstances, is very rigid and serviceable. It is retained in place by bolts 15' in a manner similar to that employed in the construction previously described. 80

Figs. 6 and 7 illustrate a modified form of bolt mounting in which the hole in the tie 8" is enlarged at one side of the tie and a metal washer 21 inserted in the enlargement. This washer is provided with lugs 85 22 on the sides thereof thereby preventing rotation of the washer after it is inserted in the enlargement of the bolt hole. The washer is also provided with a square re- 90 cess 23 adapted to receive the head of the bolt and prevent rotation thereof. With this construction the bolt is protected and the end thereof insulated from the ground. As a further precaution a plain wooden strip may be nailed across the openings in 95 the tie.

It is obvious that many changes in detail may be made in the construction of the device without departing from the spirit of the invention, and the invention is not 100 limited to the specific means herein shown.

What I claim is:

1. A tie plate for rails comprising in combination a base plate adapted to rest upon the upper surface of a tie and provided with 105 a depending flange, means on the plate for securing the plate to the rail, a bolt for securing the tie plate to the tie extending through a hole in the tie from one side to the other and adapted to pass through the depending flange of the tie plate, means for securing the bolt against removal, and means for insulating the bolt and securing means from contact with external objects.

2. A tie plate for rails comprising in combination a base plate adapted to rest upon the upper surface of a tie and provided with a depending flange, means on the plate for securing the plate to the rail, a bolt for screwing the tie plate to the tie extending 110 through a hole in the tie from one side to the other and adapted to pass through the depending flange of the tie plate, means for securing the bolt against removal, and means attached to the tie for insulating the bolt 120 and securing means from contact with external objects.

3. A tie plate for supporting railway rails,

comprising a metal plate provided with a pair of diagonally spaced lugs adapted to overlap the base flange of the rail when in operative position with respect to the rail and to clear the base flange of the rail when the plate is diagonally positioned with respect to the rail, an integral depending flange extending entirely across the end of the plate adapted to engage the side of the tie when the plate is in operative position with respect to the rail, and means engaging the flange adjacent the ends thereof for binding the flange to the tie. 10

CHARLES D. YOUNG.
